UNITED STATES PATENT OFFICE

163,601

HOUSING FOR AN ELECTRONIC SOUND RECORDER

Lawrence M. Heineman, Los Angeles, Calif., assignor to Permoflux Corporation, Chicago, Ill., a corporation of Illinois

Application February 21, 1951, Serial No. 14,291

Term of patent 14 years

(Cl. D26—14)

To all whom it may concern:

Be it known that I, Lawrence M. Heineman, a citizen of the United States, residing at Los Angeles, in the county of Los Angeles and State of California, have invented a new, original, and ornamental Design for a Housing for an Electronic Sound Recorder, of which the following is a specification, reference being made to the accompanying drawing, forming a part hereof.

In the drawings:

Fig. 1 is a front perspective view of a housing for an electronic sound recorder embodying my novel design;

Fig. 2 is a right-hand side elevational view thereof; and

Fig. 3 is a rear elevational view thereof.

I claim:

The ornamental design for a housing for an electronic sound recorder, substantially as shown.

LAWRENCE M. HEINEMAN.
